UNITED STATES PATENT OFFICE.

EDWARD D. WOODS, OF GRANVILLE, NEW YORK.

DESIGN FOR A SICKLE.

SPECIFICATION forming part of Design No. 29,626, dated November 8, 1898.

Application filed March 22, 1898. Serial No. 674,835. Term of patent 14 years.

To all whom it may concern:

Be it known that I, EDWARD D. WOODS, a citizen of the United States, and a resident of Granville, Washington county, State of New York, have invented a certain new and original Design for Sickles, of which the following is a specification.

My invention consists in a design for sickles.

Figure 1 is a face view of a sickle embodying my design, and Fig. 2 is a cross-section on the line 2 2 of Fig. 1.

A is the blade and B the handle of the sickle. The blade has a wavy cutting edge C. The surface of the upper side of the blade

near its edge is curved upward from the cutting edge to the plane of the upper surface of the blade, as shown in cross-section in Fig. 2.

What I claim as new, and desire to secure by Letters Patent, is—

The design for a sickle substantially as herein described and shown.

In testimony whereof I have signed my name to this specification in the presence of two subscribing witnesses.

EDWARD D. WOODS.

Witnesses:

F. T. PEMBER,
H. T. SEYMOUR.
